UNITED STATES PATENT OFFICE.

JAMES A. HORNE, OF DENVER, COLORADO.

PROPELLER DEVICE FOR AEROPLANES.

1,279,698.

Specification of Letters Patent. Patented Sept. 24, 1918.

Application filed April 26, 1917. Serial No. 164,698.

To all whom it may concern:

Be it known that I, JAMES A. HORNE, a citizen of the United States, residing at Denver, in the county of Denver and State of Colorado, have invented certain new and useful Improvements in Propeller Devices for Aeroplanes, of which the following is a specification:

This invention relates to improvements in propeller devices, more particularly to devices of this character adapted for use in connection with air craft, but which may also be applied to water craft, and has for one of its objects to improve the construction and increase the efficiency and utility of devices of this character.

Another object of the invention is to provide a device of this character having a pressure relieving attachment whereby the resistance is less at the return stroke than at the forward stroke.

With these and other objects in view, the invention consists in certain novel features of construction, as hereinafter shown and described and then specifically pointed out in the claims. For the purpose of illustration the improved device is shown applied to the framework of a conventional aeroplane and, in the drawings thus employed:

Figure 1 is a side elevation of a portion of an aeroplane frame including the support for the motor and steering apparatus, portions of the planes, and the supporting frame therefor, with the improvement applied;

Fig. 2 is a front elevation of the parts shown in Fig. 1;

Fig. 3 is an enlarged vertical section of one of the bucket devices;

Fig. 4 is an enlarged transverse section of one of the bucket devices;

Fig. 5 is an enlarged sectional detail illustrating the construction of the reversing and controlling mechanism;

Fig. 6 is a transverse section on the line 6-6 of Fig. 5 looking in the direction of the arrow;

Fig. 7 is a transverse section on the line 7-7 of Fig. 5 looking in the direction of the arrow.

The support for the motor and the steering apparatus is represented as a whole at 10,

the supporting framework for the planes at 11, the "planes" at 12-13. The motor indicated at 14 is of any suitable construction. The improved device includes main driving shafts 15-16 mounted for rotation in suitable bearings 17-18 upon the frame 11, the shafts being disposed in longitudinal alignment and coupled for independent rotation at their inner ends, as indicated at 19. The shafts 15-16 are provided respectively with belt pulleys 20-21 over which belts 22-23 lead from the motor 14, the motor being so geared as to independently operate the drive belts 22-23, the means for independently driving the shafts not being shown as it forms no part of the present invention.

The propelling devices are mounted upon the shafts 15-16 at each side of the center of the frame 11, and as these propelling devices are precisely alike the description of one will suffice for both. Each propelling device includes arms 24-25 mounted for rotation with the shafts 15-16 and disposed at spaced intervals thereon. The arms 24-25 are mounted intermediate their ends respectively on the shafts 15-16, and provided at their outer ends with bearings 26 to receive shafts 27. Mounted upon each of the shafts 27 are the bucket devices, each bucket device comprising a body member 28 semicircular longitudinally, as shown in Figs. 1 and 3 and reversely curved transversely as shown in Fig. 4.

Each bucket is thus substantially in the form of a double end skiff or like boat, closed at one side and open at the other side.

One of the shafts 27 extend through each of the buckets and is rigidly secured thereto in any suitable manner. Mounted loosely upon each of the shafts 15-16 is a sleeve 30 and rigidly coupled to the sleeves are chain wheels 31-32 arranged side by side.

One of the shafts 27 of each of the set of buckets is provided with a chain pinion 33, while the shaft 27 of the other bucket of the same set is provided with a chain pinion 34. A chain 35 extends over the chain wheel 31 and the pinion 33 while a similar chain 36 extends over the chain wheel 32 and the pinion 34.

Means are provided for holding the sleeve 30 rigidly in position and reversing the position of the same to correspondingly reverse the position of the buckets. For the 5 purpose of illustration a reversing mechanism is shown comprising a toothed segment 37 rigidly coupled to a support 38 attached to the frame 11. Extending from the sleeve 30 and preferably integral therewith is an arm 39 having a pawl device 40 pivoted thereto and adapted to engage in the notches of the segment 37. The sleeve 30 is thus held stationary at either one of 10 two points to the notches in the segment 37. 15 Extending from the sleeve 30 are cable guide loops 41 through which pull cords or cables 42-43 extend, the pull cables being both connected to the pawl 39. The cables are likewise provided respectively with stops 20 44-45, initially spaced from the pawl 39. The pull cables lead to a point convenient to the operator in the housing 10. It will be noted that the chain wheels 31-32 are the same diameter as the pinions 33-34, hence by moving the arm 39 one 25 half of a revolution around the shaft 27 the larger chain wheels 32 will cause the pinions 33-34 to rotate half a revolution, and thus reverse the position of the buckets 30 upon the shaft. By this arrangement when the motor 14 is actuated the shafts 15-16 will be continuously rotated together with the arms 24, and by holding the sleeve 30 and the chain wheels 31-32 in fixed relation 35 to the shaft, the open sides of the buckets will be caused to move constantly in a vertical position, or operating with a planetary movement relative to the shaft, thus producing a "feathering" action. 40 The notches in the member 37 will be so disposed that when the pawl device 40 is engaged with the terminal notch at one side the buckets will be held with their open sides directed forwardly as shown in Fig. 45 1, then when the pawl device is disposed in engagement with the terminal notch at the opposite side the buckets will be reversed in position or with their open sides pointing rearwardly. By providing a plurality of 50 notches the buckets may be disposed with their open sides obliquely to the vertical which may be necessary when employing the device in connection with an aeroplane. By employing the stops 44-45 it will be noted 55 that when either of the cables is first pulled downwardly by the operator the first movement will not actuate the sleeve, but will release the pawl device 39, and then when the stop 44 or 45, as the case may be, comes 60 in contact with the loops 41 the sleeve will be "picked up" and rotate to a required extent. If the buckets are to be entirely reversed in position the pull member 42 or 43 will be actuated until the pawl 39 is opposite 65 the terminal notch of the segment, and

when the pull cable is released the pawl will fall by gravity into the adjacent notch and thus lock the mechanism and hold the bucket in position.

The body portion of each of the buckets 70 is provided with openings 46 closed by valves 47 hingedly united at 48 to the inner face of the body of the bucket at each side of a medial line. The valves 47 thus swing inwardly and admit air from the outside 75 but will not permit air to pass from the inside of the bucket through the openings.

By employing the valves the resistance of air at the return stroke is materially decreased, while the force of the forward 80 stroke is not diminished. The action will be the same whether the buckets be employed upon air crafts or water crafts, as will be obvious.

The buckets and attachments may be constructed of any suitable material, but will be as light as possible consistent with the strains to which they will be subjected when in use.

By this arrangement also the buckets may 90 be reversed in position to cause the vehicle to which they are attached to move forwardly or rearwardly as may be preferred. The mechanism for driving the shafts 15-16 are independently arranged so that 95 the shafts and the buckets with which they are associated may be operated simultaneously or separately, or one shaft with its buckets rotated forwardly while the other is rotated rearwardly or vice-versa. By this 100 means the motion is under complete control of the operator.

A stop 50 will preferably be connected within each bucket to limit the opening movement of the valves.

Having thus described the invention, what is claimed as new is:

1. In propelling mechanism, a bucket with one side open and the walls sloping from a medial line toward the open side, said bucket having openings spaced from the medial line with their contiguous edges in parallel relation, closing valves hinged to the contiguous edges of said openings and swinging toward each other, and a stop between 110 the valves and limiting their inward movement.

2. In a propelling mechanism, a bucket with one side open and the walls of the remaining portion reversely curved longitudinally and transversely from a medial line, so that the outer faces slope in reverse curves toward the open side to reduce the resistance during the return stroke, said bucket having openings at each side of the medial line with their contiguous edges extending in parallel relation, and closing valves hinged to the contiguous edges of said openings and swinging toward each other, whereby the force of the air currents 120 25 130

passing through the valved openings is equalized and uniform pressure maintained during the return stroke.

3. A bucket open at one side with the walls reversely sloping from a medial line toward the open side, said sloping walls each having an opening with their contigu-

ous edges in parallel relation and spaced from said medial line, and closure valves for said openings hinged respectively to the contiguous edges of the openings and opening toward each other.

In testimony whereof I affix my signature.

JAMES A. HORNE. [L. S.]
